CLAIM

The ornamental design for a desk lamp, as shown and described.

DESCRIPTION

The claimed desk lamp is a device that generates light, heat, or therapeutic radiation to be used on a desk.

FIG. 1 is a front elevational view of a desk lamp showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
